RAILWAY SWITCH OPERATING APPARATUS

Herbert L. Bone, Forest Hills, Pa., assignor to The Union Switch & Signal Company, Swissvale, Pa., a corporation of Pennsylvania

Application April 8, 1941, Serial No. 387,385

18 Claims. (Cl. 246—240)

My invention relates to railway switch operating apparatus, and particularly to railway switch operating apparatus of the so-called "dual-control" type in which means are provided for operating a switch either by power or by hand depending upon the position of a manually operable selector lever.

One object of my invention is the provision, in apparatus of the type described, of a new and improved dual-control mechanism the manual operation of which is normally effective to cause the switch to become locked in either extreme position to which it is moved in the same manner that the switch becomes locked in either extreme position to which it is moved in response to power operation of the mechanism, but which mechanism is so arranged that the hand throw lever can, by proper manipulation of the selector lever, be rendered effective to move the switch points to, and hold them in, either extreme position, without moving the locking plunger to its locking position. This operation is advantageous, since in the ordinary applications of dual-control switch and lock movements, the signals governing traffic over the switch are usually controlled by a circuit controller operated in part by the locking plunger in such manner that the signals cannot clear unless the switch points are moved to one or the other of their extreme positions and are locked in these positions, and it is normally desirable that the signals should clear in response to manual operation of the switch in the same manner as when the mechanism is operated by power. However, it sometimes happens that the lock rods become fouled, due for example to dragging equipment or to improper maintenance, without the switch being otherwise damaged, and in this event it is desirable to be able to reverse the switch to permit train movements over the switch without having the signals clear.

Another object of my invention is the provision in a dual-control mechanism for switch operating apparatus of the type described of a new and improved clutch mechanism for operatively connecting the hand throw and power operated gear trains with the main switch operating crank in such manner that the main switch operating crank can never be simultaneously disconnected from both gear trains.

A further object of my invention is the provision in a dual-control mechanism for switch operating apparatus of the type described of a clutch mechanism of the type described which, while permitting the selector lever to be oper-

ated to its full stroke even though the relative positions of the switch, power gearing and hand throw gearing are not in agreement at the time, will give a positive "break-apart" motion guaranteeing separation of the previously engaged drive.

Other objects and characteristic features of my invention will become apparent as the description proceeds.

10 I accomplish the aforementioned objects by the details of construction hereinafter set forth.

I shall describe one form of apparatus embodying my invention, and shall then point out the novel features thereof in claims.

15 In the accompanying drawings, Fig. 1 is a vertical sectional view showing one form of apparatus embodying my invention. Fig. 2 is a left-hand side view partly in elevation, and partly in section, of the apparatus shown in Fig. 1.

20 Fig. 3 is a sectional view taken substantially on the line III—III of Fig. 2. Fig. 4 is a view partly diagrammatic and partly in horizontal section showing certain parts of the apparatus illustrated in the preceding views connected with a railway switch in the intended manner. Fig. 5 is a view taken on the line V—V of Fig. 4.

25 Similar reference characters refer to similar parts in each of the several views.

Referring to the drawings, the reference character 1 designates a housing provided with a removable cover 2, and adapted to be mounted adjacent a railway track switch S shown diagrammatically in Fig. 4. Journaled in vertically aligned bearings 3 and 4 disposed within the

30 housing 1 is a vertically extending shaft 6, the lower end of which terminates in a crank 7. This crank extends in opposite directions from the shaft, and is provided on its lower side with a crank pin 8 carrying a roller 9, and on its upper side with rounded upstanding projections 10 and 11 disposed on opposite sides of the shaft. The roller 9 cooperates with a cam slot 9a formed in an operating rod O, while the projections 10 and 11 cooperate, respectively, with spaced recesses 10a and 11a formed in the underside of a slide bar N. The operating rod O is slidably mounted in the bottom of the casing 1 at one side of the axis of the shaft 6 and is operatively connected at one of its outer ends with the switch S. The slide bar N is slidably mounted in the bottom of the casing 1 in a position in which it intersects the operating rod O at right angles, and is provided at its right-hand end with a locking plunger 12

35 provided with vertically offset and longitudinally

40 45 50 55

spaced locking dogs 12a and 12b which are adapted to selectively enter spaced notches 13a and 13b provided in a lock rod L operatively connected with the switch points of the switch S. The lock rod L is of well-known construction, and is slidably mounted in the bottom of the casing I at right angles to the slide bar N, as is obvious.

The portion of the switch operating apparatus thus far described is essentially the same as that described and claimed in Letters Patent of the United States No. 1,293,290, granted to William Zabel on February 4, 1919, for Railway traffic controlling apparatus, and its operation, briefly described, is as follows: When the operating rod O and the slide bar N are in their normal positions, and the switch points of the switch S are in their corresponding positions, as shown in Fig. 4, the locking dog 12a is disposed within the notches 13a in the lock rod L, and under these conditions the switch points are securely locked in their normal positions by the locking dog 12a.

When it is desired to reverse the switch S, the shaft 6 is rotated in a clockwise direction from the extreme position shown to its opposite extreme position. The initial part of this rotation, usually about the first 30°, causes the projection 10 on the crank 7 to engage the left-hand wall of the recess 10a in the slide bar N, and move the slide bar toward the left far enough to withdraw the locking dog 12a from the notches 13a in the lock rod L. During this initial movement of the crank the roller 9 whose initial position was at the left-hand end of the cam slot 9a is moved to the medial portion of the slot, that is to say, to a point just a little to the left of the junction of the curved and straight walls thereof, but due to the curvature of the upper wall of the cam slot, this movement of the roller does not cause any movement of the operating rod O. It will be seen, therefore, that during the first part of the movement of the crank 7, the slide bar N is moved to unlock the switch points, but the operating rod O and the switch points remain stationary. However, in the continued movement of the crank, the roller 9 engages the lower straight side of the cam slot 9a and moves the operating rod O in the direction that the crank is moving to thereby move the switch points to their reverse positions. This latter or intermediate movement of the crank will usually rotate the crank through an angle of approximately 180°. Upon further continued movement of the crank, projection 11 enters the recess 11a and imparts a second movement to the slide bar N in the same direction as the first movement, which latter movement causes the locking dog 12b to enter the notches 13b in the lock rod L and lock the switch in its reverse position.

When the parts have been operated to the positions just described, and the crank is rotated in a counterclockwise direction to restore the parts to the positions shown, the sequence of movements of the operating rod and slide bar are maintained, but the directions of the movements are reversed.

For convenience I shall hereinafter refer to the initial movement of the crank from either extreme position towards the other as the unlocking stroke, the intermediate portion as the switch operating stroke, and the final movement as the locking stroke.

It should be particularly pointed out that with the apparatus constructed in the manner just described, upon the completion of the switch op-

erating stroke in either direction of rotation of the crank 7, the roller 9 will have just entered the curved portion of the cam slot 9a, and that when the parts are in these positions if the crank is

5 prevented from rotating in the direction to move the roller out of the curved portion of the cam slot, the switch will be effectively held, by the cooperation between the roller and the operating rod, in the extreme position it then occupies irrespective of the fact that it is unlocked. It follows, therefore, that if suitable precautions are taken to prevent the crank from creeping upon the completion of the switch operating stroke, trains can be safely moved over the switch even 10 though it is not locked by the locking plunger. One way for preventing the crank from creeping which can be used consists in providing the operating motor M of the mechanism shown diagrammatically in Fig. 2, with a magnetic brake similar 15 to that shown and described in Letters Patent of the United States No. 2,183,164, granted to William C. McWhirter et al. on December 12, 1939, for Railway switch operating apparatus.

A main bevel gear 15 is rotatably mounted on 20 the shaft 6 directly above the lower bearing 4, and is operatively connected with power driving means here shown as the electric motor M, through suitable reduction gearing indicated in the drawing by the dash line 16. An auxiliary bevel gear 17 is also rotatably mounted on the 25 shaft 6 between the upper bearing 3 and the upper end of a bushing 18, the lower end of which bushing rests on a shoulder 19 formed on the shaft 6. The bevel gear 17 meshes with a second bevel gear 20 fixed to a horizontal shaft 21 rotatably mounted within a sleeve 22, which sleeve, in turn, is rotatably mounted in a boss 40 provided in the wall of the casing I. The shaft 21 30 projects through the sleeve 22 and carries at its outer end a hand throw lever 23 which is at times used for manual operation of the switch.

In accordance with my present invention, novel and improved means are provided for selectively connecting the bevel gear 15 or the bevel gear 17 with the switch actuating shaft 6 to permit the switch to be operated either by the electric motor M or by the hand lever 23. As here shown, these means comprise a clutch assembly A consisting of two sleeves 24 and 25 which are mounted on the shaft 6 for vertical sliding movement between the two gears 15 and 17, but which are constrained to rotate with the shaft 6 by means of integral internal splines 26 which cooperate with corresponding splines 27 formed on the shaft. The two sleeves 24 and 25 are secured together at their confronting ends to cause them to act as a unit, and are provided at their upper and lower ends, respectively, with circumferential flanges 24a and 25a which form confronting shoulders 24b and 25b. Surrounding the sleeves 24 and 25 between the shoulders 24b and 25b is a compressed coil spring 28. One end of the spring engages a flat spring thrust washer 26 and constantly urges it to the position in which it engages the shoulder 24b, and the other end of this spring engages a cupped spring thrust washer 27 and constantly urges it to the position in which it engages the shoulder 25b.

The lower end of the sleeve 25 is formed with 70 tapered projections 29 which cooperate with tapered recesses 30 provided in the hub of the bevel gear 6, whereby when the clutch mechanism is in its lower position as shown, the shaft 6 is connected to the main bevel gear 15 to enable the mechanism to be power operated in the nor-

mal manner. The projections 29 are evenly spaced about the sleeve, four such projections being provided. It will be seen, therefore, that with the parts constructed as shown, the clutch can become connected with the gear wheel 15 in any one of four angular positions. It should be understood, however, that any desired number of projections may be provided.

The upper end of the sleeve 24 is formed with a single projection 31 which cooperates with a stepped recess 32 having a narrow upper portion 32a and a wider lower portion 32b. The narrow upper portion 32a of the recess 32 is just wide enough to receive the projection 31 without binding when the portion 32a is in vertical alignment with the projection 31 and the clutch member is moved to its upper extreme position, and the parts are so proportioned that when the projection 31 is in the narrow portion 32a of the recess 32, rotation of the hand throw lever 23 between its two extreme positions will rotate the switch actuating shaft between its two extreme positions in the same manner that this shaft is rotated between its two extreme positions by power operation when the clutch is in engagement with the bevel gear 15. With the mechanism constructed as shown, the switch operating stroke of the shaft 6 is 140°, and the switch locking and unlocking strokes are each 40°, making the total stroke for the switch actuating shaft of 220°. The projection 31 has an angular length of slightly less than 180°, while the narrow portion 32a of the recess has an angular length of slightly more than 180°. It will be understood, however, that this proportioning of the parts is merely given by way of example, and not by way of limitation, and that other satisfactory proportionings of the parts may readily be effected.

The wide portion 32b of the recess 32 is sufficiently long and is so disposed on the gear 17 that when the projection 31 is in this portion of the recess, sufficient lost motion will be introduced between the hand throw lever and the shaft 6 so that rotation of the hand throw lever from either extreme position to the other will rotate the shaft 6 to the end of its switch operating stroke but not further. With the proportioning of the parts assumed in the preceding paragraph, the desired operation may, for example, be obtained by making the wide portion 240° long with its ends each disposed 30° from the adjacent ends of the narrow portion.

The overall length of the clutch assembly including the projections 29 and 31 is such that when the assembly occupies its lower position, it will become completely disengaged from the gear 17, and that when it occupies its upper position, it will be completely disengaged from the gear 15, but that, it cannot be completely disengaged from one gear until it has first become engaged with the other gear. It follows, therefore, that the shaft 6 will always be engaged with either the power or the hand throw gearing. This is important for reasons which will appear herein-after.

The clutch assembly A is arranged to be moved longitudinally on the shaft 6 in order to effect the desired driving connection between the bevel gear 17 and the shaft 6 or the bevel gear 15 and the shaft 6 by means of a shifter fork 35 comprising two spaced triangular arms 35a and 35b connected together intermediate their ends by a yoke 35c. This shifter fork is pivotally supported at one end on a pin 36 mounted in a lug 37 cast on the

side wall of the housing 1, and the arms thereof at the ends opposite to the pin are curved outwardly and extended on opposite sides of the clutch assembly A to positions beyond the vertical axis of the assembly. Secured to the inner curved ends of each arm is a pair of spaced rollers 38, the upper one of which overlies the spring washer 26 and the lower one of which underlies an annular outwardly extending flange 27a formed on the spring washer 27. The spacing between the two rollers on each arm is made slightly greater than the spacing between the upper side of the washer 26 and the lower side of the flange 27a on the washer 27 when these washers are engaging the associated shoulders 24b and 25b, for a purpose which will appear hereinafter.

Intermediate their ends, the arms 35a and 35b are pierced by aligned openings which receive with clearance the central circular portion of a rotatable shaft 39, the rounded ends of which are smaller than the central portion of the shaft and are eccentrically disposed with respect to the axis of the central portion of the shaft. The shaft 39 is journaled at its ends in bearings 41 and 42 removably secured within suitable openings provided in the opposite side walls of the housing 1, and has mounted thereon at the end nearest the gear 20 a spur gear 43 which meshes with and is driven by a spur gear 44 secured to the inner end of the previously described sleeve 22. The sleeve 22 extends outwardly through the boss 40 and is provided at its outer end with a selector lever 47 disposed between the boss and the hand throw lever 23.

The operation, as a whole, of the portion of the apparatus thus far described is as follows. Normally, the selector and hand throw levers both occupy the positions in which they are shown in the drawings, which is the position for power operation, and under these conditions, the eccentric shaft 39 is held by the intermeshing gears 44 and 43 in the position in which the axis of the enlarged central portion is below the axis of rotation of the shaft. When the eccentric shaft occupies this position, the shifter fork 35 is rotated by the shaft to its lowermost position, and the parts are so proportioned that if the projections 29 on the lower end of the clutch sleeve 25 are then in alignment with the recesses 30 in the bevel gear 15, the clutch will move to its lowermost position and will thereby condition the apparatus for power operation in the manner pointed out hereinbefore. When the clutch assembly is in its lowermost position, it is supported by the top face of the hub of the gear 15, and the parts are further so proportioned that all four rollers 38 will be clear of the spring thrust washers 26 and 27, so that under power operation no load is carried by the rollers. It will be understood, of course, that when the mechanism is operated by the motor, the switch actuating shaft 6 will be rotated through its full operating stroke, so that the switch will become locked in either extreme position to which it is moved.

If, when the selector lever is moved to the power operating position, as shown, the projections 29 on the clutch sleeve 25 do not align with the recesses 30 on the hub of the bevel gear 15, so that the clutch sleeve is prevented from moving to its lowermost extreme position by engagement of the lower ends of the projections 29 with the upper side of the hub of the bevel gear, the shifter fork 35 will still be rotated to its lowermost position, but under these latter conditions, the rollers

38 will act through the spring thrust washer 26 to exert a force on the spring 28 which causes it to become compressed and bias the clutch assembly to its lowermost position. As a result, as soon as the bevel gear 15 is rotated by the motor to the positions in which the projections 29 align with the recesses 30, the clutch will immediately snap to its lowermost position in which it is shown in the drawings.

When the switch is in condition for motor operation, the bevel gear 17 is disconnected from the switch actuating shaft 6, and the hand throw lever is therefore disconnected from the switch.

When it is desired to disconnect the motor from, and connect the hand throw lever 23 with the shaft 6, the selector lever is rotated from the motor operating position in which it is shown in the drawings to its opposite extreme or hand throw position. This rotation acts through the sleeve 22 and the gears 44 and 43 to rotate the shifter shaft 39 from the position shown through an angle of 180° to the position in which the axis of the central enlarged portion of the shaft is disposed at the highest point in its travel, and hence causes the shifter fork 35 to rotate from its lowermost to its uppermost position. During this rotation the lower roller 38 on the shifter fork engages the underside of the flange 27a on the spring thrust washer 27 and moves it upwardly with the shifter fork. The upward movement of the spring washer, in turn, exerts a force on the spring 38 which is transmitted through the spring and thrust washer 26 to the interconnected clutch sleeves, and under normal conditions, this force will cause the sleeves to move upwardly as soon as the shifter fork starts to move. However, should the switch operating apparatus happen to be standing with the power gear train stopped by the inertia of the rotating parts upon the completion of the previous reversal of the movement, the static torque which then exists between the engaging sides of the projections 29 and recesses 30, may be sufficient to prevent the assembly from starting to move upwardly even though spring 28 becomes fully compressed. The parts are so proportioned that under these latter conditions, the flange 27a will move into engagement with the spring washer 26 before the shifter fork reaches its upper extreme position, and when this happens, a positive force will be exerted on the clutch sleeve which force is sufficient to overcome the static torque between the lower sleeve and the gear wheel 15, and will thus cause the clutch assembly as a whole to move upwardly under the bias of the compressed spring 28.

When the clutch assembly starts to move upwardly, if the narrow portion 32a of the recess 32 in the bevel gear 17 is then in alignment with the projection 31 on the sleeve 24 as will be the case when the switch and hand lever occupy corresponding extreme positions and the switch is fully locked in the extreme position it then occupies, the spring 28 will act to cause the clutch to move to its upper extreme position in which the projection 31 enters the narrow portion of the recess 32. The bevel gear 17 will then be connected with the shaft 6 in such manner that the switch may be rotated between its two extreme positions and locked in either extreme position to which it is moved by the hand lever in the same manner that it is rotated between its two extreme positions and is locked in either extreme position by power operation. If, however, the narrow portion 32a of the recess 32 in the bevel

gear 17 is not in alignment with the projection 31 on the sleeve 24 of the clutch assembly when the clutch assembly starts to move upwardly, the spring 28 will then act to move the clutch assembly to the position in which it enters the wide portion of the recess 32, but full upward movement of the clutch will be prevented. Under these conditions, the spring 28 will become compressed, and as soon as the hand throw lever is rotated to the position in which the narrow portion 32a of the recess 32 aligns with the projection 31, the spring 28 will act to force the clutch assembly to its full upper position. This alignment of the narrow portion of the recess with the projection 31 will always occur at some point in the stroke of the hand throw lever, and if the switch happens to be in a position opposite to that of the hand throw lever when the selector lever is operated to the hand throw position, 20 then the hand throw lever will rotate freely without engaging the clutch until the hand throw lever is fully reversed.

I shall now assume that the lock rods of the switch have become damaged or are out of adjustment, but that the switch is otherwise in operating condition, and that it is desired to reverse the switch by hand without locking it up. To accomplish this result, the operator will move the selector lever to the hand throw position in 30 the manner previously described, and will then operate the hand throw lever. If the parts are in such positions that the projections 31 on the upper clutch sleeve 24 enter the wide portion 32b of the recess 32 in the bevel gear 17 when 35 the selector lever is reversed, then the hand throw lever upon being reversed will just rotate the switch operating shaft to the end of the switch operating stroke, and the desired result will be obtained without further manipulation 40 of the mechanism. If, however, the projection 31 enters the narrow portion of the recess 32 in response to movement of the selector lever to its hand throw position, then when the hand throw lever is subsequently operated, its movement will 45 be arrested when the switch actuating shaft reaches the position in which the locking dog fouls the lock rod. Under these latter conditions, it is desired to be able to complete the stroke of the hand throw lever, and this result may be accomplished by lifting the selector lever to its 50 vertical position. This movement will force the clutch assembly downwardly to the position in which the projection 31 moves out of the narrow portion 32a of the recess 32 and into the wide portion 32b, and as soon as the projection 31 is clear of the narrow portion 32a of the recess 32, the hand lever 23 will drop by gravity to its 55 full stroke position. The selector lever may then be restored to either the motor or hand throw position as desired. When the hand throw lever reaches its full stroke position, it will be held in this position by the usual lever latch stand, not shown, and since the roller 9 will then be within the curved portion of the cam slot 9a in the operating rod O, the switch will be securely held in its reverse position even though it is not locked in this position by the lock rod, as pointed out hereinbefore. Since the switch is securely held in its reverse position, trains can be safely moved 60 over the switch.

If it is attempted to reverse the switch when it is damaged or obstructed to such an extent that the operating rod O cannot complete its full stroke, the hand throw lever cannot be forced 75 into the latch stand even if the selector lever is

operated to cause projection 31 to enter the wide portion 32b of recess 32. This is due to the fact that the lost motion provided by the wide portion 32b of recess 32 is only sufficient to permit the hand throw lever to enter the latch stand when the operating rod has fully completed its stroke. The fact that the hand throw lever cannot enter the latch stand indicates to the switchman that the switch is not in proper condition for train movements over it.

The switch operating apparatus will usually include a circuit controller, not shown, which may be similar to that described in Patent No. 1,293,290 referred to hereinbefore. This circuit controller may be used to govern signals controlling traffic movements over the switch operated by the mechanism, and when so used it will be apparent that the signals will only clear when the switch occupies one or the other of its extreme positions and is fully locked in such extreme position.

It follows from the foregoing that my present invention provides for the manual operation of a power operated switch in such a way that the switch will normally become locked in response to manual operation to cause the signals to clear in the same manner as when the switch is operated by power, but that, in the event of lock rod fouling, if the switch is otherwise undamaged, it can, by proper manipulation of the apparatus, be reversed without locking the switch in its reverse position.

The apparatus also includes means for interlocking the selector and hand throw levers in such manner that the hand throw lever cannot be operated unless the selector lever occupies the hand throw position. As here shown, these means comprise cooperating interlocking discs 45 and 46 formed respectively on the hub of the gear wheel 43 and on the hub of the bevel gear 20. Disc 45 is provided with an arcuate projection 45a which, when the selector lever occupies its power operating position, enters a mating arcuate notch 46a or 46b in disc 46 according as the hand throw lever then occupies its normal extreme position in which it is shown in the drawing or its opposite extreme position. The length of the projection 45a is such that it will remain in one or the other of the recesses 46a or 46b when the selector lever is rotated towards the hand throw position until the selector lever has been moved to approximately its mid stroke position. It will be apparent that when the projection 45a is within one or the other of the arcuate notches 46a and 46b, rotation of the hand throw lever is effectively prevented, and it follows, therefore, that the discs act to prevent rotation of the hand throw lever except when the selector lever is in its hand throw position.

One advantage of switch operating apparatus embodying my invention is that since the clutch is always effective to connect either the hand throw lever or the motor operating gear train with the switch operating shaft, the switch operating rod is clearly held from movement regardless of the positions of the selector and hand throw levers. This is of particular significance when the power is off.

Although I have herein shown and described only one form of railway switch operating apparatus embodying my invention, it is understood that various changes and modifications may be made therein within the scope of the appended claims without departing from the spirit and scope of my invention.

Having thus described my invention, what I claim is:

1. In railway switch operating apparatus including means responsive to rotation of a main operating shaft to one extent for unlocking and reversing the switch and to another extent for locking the switch, the combination of manual means and power means for optionally operating said shaft, and selector means for connecting said manual means or said power means with said shaft, said selector means including means for optionally rendering said manual means effective to rotate said shaft to its one or its other extent in response to full stroke operation of said manual means.
2. In combination with an operating rod for operating a railway track switch and a slide bar for locking the switch, a rotatable shaft for operating the operating rod in response to rotation of said shaft to one extent and both the operating rod and slide bar in response to rotation of said shaft to a greater extent, power and manual means for optionally operating said shaft, a clutch effective when moved to one position to connect said power means to said shaft to enable the shaft to be operated by the power means to its greater extent and when moved to another position to connect said manual means to said shaft to enable said shaft to be operated by said manual means to its greater extent and when moved to a third position to connect said manual means to said shaft to enable the shaft to be operated by said manual means to said one extent only, whereby the switch can be optionally locked or left unlocked following its reversal by said manual means, and means for operating said clutch.
3. In railway switch operating apparatus including means responsive to rotation of a main operating shaft to one extent for unlocking and reversing the switch and to another extent for locking the switch, the combination of manual means and power means for optionally operating said shaft, and clutch means for connecting said manual means or said power means with said shaft, said clutch means being movable to two different manual operation positions in one of which said manual means is effective in response to its full stroke operation to move said shaft to its other extent and in the other of which said manual means is effective in response to its full stroke operation to move said shaft to its one extent only.
4. In railway switch operating apparatus including means responsive to rotation of a main operating shaft to one extent for unlocking and reversing the switch and to another extent for locking the switch, the combination of manual means and power means for optionally operating said shaft, and clutch means for connecting said manual means or said power means with said shaft, said clutch means being movable to two different manual operation positions in one of which said manual means is effective in response to its full stroke operation to move said shaft to its other extent and in the other of which sufficient lost motion is introduced between said manual means and said shaft to prevent operation of said shaft beyond its one extent by said manual means.
5. Railway switch operating apparatus comprising a rotatable switch actuating shaft, two movable members associated with said shaft, and a manually operable clutch associated with said shaft and movable to one position in which the

one member becomes connected with said shaft and to two other positions in both of which the other member becomes connected with the shaft, one of said other positions providing some lost motion between said shaft and said other member.

6. Railway switch operating apparatus comprising a rotatable switch actuating shaft, two driving members rotatably mounted on said shaft in spaced confronting relation, means for rotating said members, a clutch assembly mounted on said shaft to rotate therewith between said driving members but slidable thereon toward one or the other of said members, means connecting said one member with said shaft when said clutch assembly is moved into engagement with said one member, other means connecting said other member with said shaft with a predetermined amount of lost motion or substantially without lost motion when said clutch assembly is moved toward said other member depending upon the extent to which said clutch assembly is moved toward said other member, and means for moving said clutch assembly along said shaft.

7. Railway switch operating apparatus comprising a rotatable switch actuating shaft, a gear wheel rotatably mounted on said shaft and provided with a stepped recess having a wide portion and a narrow portion, a clutch assembly mounted on said shaft to rotate therewith but slidable thereon toward and away from said gear wheel, said clutch assembly being provided with a projection which is adapted to enter the wide or narrow portions of said recess to cause said gear wheel to become connected with said shaft with or without lost motion depending upon the extent of movement of said clutch assembly toward said gear wheel, and means for sliding said clutch assembly toward said gear wheel to different extents and away from said gear wheel.

8. In railway switch operating apparatus including means responsive to rotation of a main operating shaft to one extent for unlocking and reversing the switch and to a greater extent for relocking the switch, a gear wheel rotatably mounted on said shaft and provided with a stepped recess having a wide portion and a narrow portion, a clutch assembly mounted on said shaft to rotate therewith but slidable thereon toward and away from said gear wheel, said clutch assembly being provided with a projection which is adapted to enter the wide or narrow portion of said recess when said clutch assembly is moved toward said gear wheel depending upon the extent of the movement, and means for rotating said gear wheel between two extreme positions, the parts being so proportioned that rotation of said gear wheel between its two extreme positions will rotate said shaft to its full extent or to said one extent depending upon whether said projection is within the narrow or wide portion of said recess.

9. In railway switch operating apparatus including means responsive to rotation of a main operating shaft to one extent for unlocking and reversing the switch and to a greater extent for relocking the switch, a gear wheel rotatably mounted on said shaft, a clutch assembly mounted on said shaft to rotate therewith but slidable thereon toward and away from said gear wheel, said clutch assembly being provided with means for engaging said gear wheel with lost motion when said clutch assembly is moved toward said

gear wheel to one extent and without lost motion when said clutch assembly is moved toward said gear wheel to a greater extent, and means for rotating said gear wheel to rotate said shaft to its one or its greater extent depending upon whether said clutch is moved toward said gear wheel to its one or its greater extent.

10. In railway switch operating apparatus including a switch actuating shaft, two gear wheels rotatably mounted on said shaft in spaced confronting relation, a hand lever for rotating one of said gear wheels, power means for rotating the other gear wheel, a clutch assembly for selectively connecting said gear wheels with said shaft, said clutch assembly comprising two clutch sleeves mounted on said shaft to rotate therewith but slidable thereon between said gear wheels, said sleeves being secured together to operate as a unit and being provided at their opposite ends with circumferential flanges which form confronting shoulders, a compressed spring surrounding said sleeves between said shoulders, a spring washer disposed between each shoulder and the adjacent end of said spring, and means engaging the outer sides of said spring washers for sliding said clutch assembly along said shaft.

11. In railway switch operating apparatus including a switch actuating shaft, two gear wheels rotatably mounted on said shaft in spaced confronting relation, a hand lever for rotating one of said gear wheels, power means for rotating the other gear wheel, a clutch assembly for selectively connecting said gear wheels with said shaft, said clutch assembly comprising two clutch sleeves mounted on said shaft to rotate therewith but slidable thereon between said gear wheels, said sleeves being secured together to operate as a unit and being provided at their opposite ends with circumferential flanges which form confronting shoulders, a compressed spring surrounding said sleeves between said shoulders, a spring washer disposed between each shoulder and the adjacent end of said spring, a shifter fork pivotally supported at one end and provided at the other end with arms which straddle said clutch assembly, a pair of rollers on each arm cooperating with the outer sides of said two washers respectively, and means for rotating said shifter fork about its pivot to move said clutch assembly between the positions in which it connects said gear wheels with said shaft.

12. In railway switch operating apparatus including a switch actuating shaft, two gear wheels rotatably mounted on said shaft in spaced confronting relation, a hand lever for rotating one of said gear wheels, power means for rotating the other gear wheel, a clutch for selectively connecting said gear wheels with said shaft, said clutch being sufficiently long to insure that one or the other of said gear wheels will always be connected with said shaft, means including a spring for normally shifting said clutch, and means effective in the event of initial resistance to movement of said clutch sufficient to cause said spring to become compressed more than a predetermined amount for providing a positive initial movement of said clutch.

13. In combination, a switch actuating shaft, a hand lever and a power driven member for optionally operating said switch actuating shaft, a selector lever movable between a hand operating and a power operating position, a second shaft rotated by said selector lever, a clutch assembly operated by said second shaft for connecting said hand lever or said power driven member.

with said switch-actuating shaft according as said selector lever is moved to its hand operating or power operating position, and means for preventing operation of said hand lever unless said selector lever is in its hand operating position comprising interlocking discs secured to said second shaft and said hand lever.

14. In combination, a switch actuating shaft, a hand lever and a power driven member for optionally operating said switch actuating shaft, a selector lever movable between a hand operating and a power operating position, a second shaft rotated by said selector lever, a clutch assembly operated by said second shaft for connecting said hand lever or said power driven member with said switch actuating shaft according as said selector lever is moved to its hand operating or power operating position, and means for preventing operation of said hand lever unless said selector lever is in its hand operating position comprising interlocking discs secured to said shaft and said hand lever, the disc secured to said hand lever being provided with arcuate notches and the disc secured to said shaft being provided with an arcuate projection which enters the one notch when and only when said selector lever occupies its motor operating position and said hand lever occupies its one extreme position and which enters the other notch when and only when said selector lever occupies its motor operating position and said hand lever occupies its other extreme position.

15. In combination, a switch actuating shaft, a hand lever and a power driven member for optionally operating said switch actuating shaft, a selector lever movable between a hand operating and a power operating position, and a clutch for connecting said hand lever or said power driven member with said switch actuating shaft according as said selector lever is moved to its hand operating or power operating position, said clutch normally being connected with said selector lever through resilient means and being so constructed that operation of said clutch by said selector lever will not simultaneously disconnect said shaft from both said hand lever and said power driven member, and non-resilient means operable by said selector lever in response to initial resistance to movement of said clutch in excess of that which said resilient means when stressed a predetermined amount will overcome for effecting a positive initial movement of said clutch.

16. Railway switch operating apparatus comprising a rotatable switch actuating shaft, two movable members associated with said shaft, a clutch associated with said shaft and movable

to one position in which one member becomes connected with said shaft and to another position in which the other member becomes connected with said shaft, resilient means normally effective for shifting said clutch, and non-resilient means effective to produce a positive initial movement of said clutch in the event of initial resistance to movement of said clutch in excess of that which said resilient means when stressed a predetermined amount will overcome.

17. Railway switch operating apparatus comprising a rotatable switch actuating shaft, two movable members associated with said shaft, a clutch associated with said shaft and movable to one position in which one member becomes connected with said shaft and to another position in which the other member becomes connected with said shaft, and means for shifting said clutch including means to yieldably move it if it offers less than a predetermined resistance to movement and other means for non-yieldably moving it through a predetermined initial part of its movement if it offers more than a predetermined initial resistance to movement.

18. In railway switch operating apparatus including a switch actuating shaft, two gear wheels rotatably mounted on said shaft in spaced confronting relation, a hand lever for rotating one of said gear wheels, power means for rotating the other gear wheel, a clutch assembly for selectively connecting said gear wheels with said shaft, said clutch assembly comprising two clutch sleeves mounted on said shaft to rotate therewith but slidably thereon between said gear wheels, said sleeves being secured together to operate as a unit and being provided at their opposite ends with circumferential flanges which form confronting shoulders, a compressed spring surrounding said sleeves between said shoulders, a spring washer disposed between each shoulder and the adjacent end of said spring, a shifter fork pivotally supported at one end and provided at the other end with arms which straddle said clutch assembly, a pair of rollers on each arm cooperating with the outer sides of said two washers respectively, and means for rotating said shifter fork about its pivot to move said clutch assembly between the positions in which it connects said gear wheels with said shaft, the one spring washer being cup shaped and being formed with a flange which engages the other washer before the shifter fork reaches the end of its stroke in the event said clutch assembly offers sufficient initial resistance to movement to compress said spring more than a predetermined amount.

HERBERT L. BONE.
